UNITED STATES PATENT OFFICE.

J. BLEECKER GROOT, OF ALBANY, NEW YORK.

WIRE-BOUND BOX.

SPECIFICATION forming part of Letters Patent No. 281,264, dated July 17, 1883.

Application filed February 17, 1883. (No model.)

To all whom it may concern:

Be it known that I, J. BLEECKER GROOT, of the city and county of Albany, and State of New York, have invented certain new and 5 useful Improvements in Wire-Bound Boxes and Cases, of which the following is a specification.

My invention relates to improvements in the construction of boxes and cases that are 10 strengthened by means of encircling bands of wire; and the object of my improvements is to afford suitable protection to the corners of said boxes and cases by means of metallic protecting-pieces, that are held in place by means 15 of the binding-wires and their fastening-staples in such manner that the corners and weakened edges of the boxes will receive protection against being broken and otherwise injured by use. This object I attain by means 20 of the device illustrated in the accompanying drawings, which form part of this specification, and in which—

Figure 1 is a perspective view of an open-top box provided with my protecting corner-pieces; Fig. 2, a detached and enlarged edge view of one of my corner-pieces (containing a piece of the binding-wire) and fastening-staples; Fig. 3, an enlarged face view of a detached corner-piece as seen at the outer angle, and Fig. 4 a transverse section at the line $x-x$ of Fig. 2.

My invention is designed to remedy a well-known defect that has long existed in wire-bound boxes and cases of the usual construction. The said defect consists of an inherent weakness of the small rib of the box material that is left outside of the grooves that are cut around the box for containing the binding-wire; and this weakness, which is apparent 35 on the ends of the side pieces, is most noticeable at the corners of said side pieces, for the reason that the grooves, by being cut cross-wise of the grain of the wood, leave at those points short sections of ribs which possess so 40 little strength that they are readily split off with a slight blow; and it is obvious that from

their exposed position, and the rough usage to which such boxes are exposed, these short sections of ribs will soon be broken off from the corners of the boxes, so as to leave the binding-wires without their required support. 50

As represented in the drawings, A is the corner-protecting piece, which I preferably make in the form of a right angle from sheet metal. The said protecting-piece is provided 55 at its inner edge with a longitudinal trough-shaped depression, a , which is adapted to fit into the wire-grooves cut around the box B for containing the wire bands, whereby the box is strengthened. 60

C is the bands of binding-wire, which run through the wire-grooves in the usual manner and pass through the depressions a of the corner-protecting pieces. Said binding-wires are secured in place in the wire-grooves and corner-protecting pieces by means of the staples D; and for the purpose of more firmly securing the corner-pieces A, I preferably drive one limb of said staples, that are placed at each end of a corner-piece, through the metal of 70 which the latter is composed, while the other limb passes into the wood close beside the corner-piece, so that said staples will stand astride of the binding-wire and securely fasten it and the corner-piece in place. 75

By means of the corner-protecting pieces A, the ribs b at the corners of the box are preserved from injury, and the binding-wires C are maintained in place, so as to enable the boxes to endure a much longer term of service 80 than those of the ordinary construction.

I claim as my invention—

The combination, with a wire-bound box, B, as herein described, of the corner-protecting pieces A, each having a longitudinal trough-shaped depression, a , and secured in place by the binding-wire C, as herein specified. 85

J. BLEECKER GROOT.
